LEATHER SOLED SOCK

Alfred S. Reed, Ripon, Wis., assignor to Ripon Knitting Works, Ripon, Wis., a corporation of Wisconsin

Application January 28, 1950, Serial No. 7,540

Term of patent 7 years

(Cl. D47—7)

To all whom it may concern:

Be it known that I, Alfred S. Reed, a citizen of the United States, residing at Ripon, in the county of Fond du Lac, State of Wisconsin, have invented a new, original, and ornamental Design for a Leather Soled Sock, of which the following is a specification, reference being had to the accompanying drawing, forming a part thereof, wherein:

Figure 1 is a perspective view showing my new design for a leather soled sock;

Figure 2 is a side elevational view of the article shown in Fig. 1 with the upper portion shown fragmentarily; and

Figure 3 is a top plan view of the article shown in Figs. 1 and 2.

The dominant features of my design reside in the portions shown in solid lines.

I claim:

The ornamental design for a leather soled sock, substantially as shown and described.

ALFRED S. REED.
